CLAIM

The ornamental design for a shoe midsole, as shown and described.

DESCRIPTION

FIG. 1 is a toe end view of a shoe midsole showing my new design;

FIG. 2 is a front perspective view thereof;

FIG. 3 is a side view thereof;

FIG. 4 is a rear perspective view thereof; and,

FIG. 5 is a heel end view thereof.

The broken lines immediately adjacent to the shaded area represent unclaimed boundaries of the design. The broken lines showing the remainder of the shoe are for environmental purposes only and form no part of the claimed design.
